CLAIM

The ornamental design for a butterfly sponge mop with integral molded head, as shown and described.

DESCRIPTION

FIG. 1 is an isometric view of the butterfly sponge mop design.

FIG. 2 is a top view of the head of the butterfly sponge mop design.

FIG. 3 is a side view of the head of the butterfly sponge mop design.

FIG. 4 is a front view of the head of the butterfly sponge mop design.

FIG. 5 is a rear view of the head of the butterfly sponge mop design; and,

FIG. 6 is an isometric view of the butterfly sponge mop design in a squeezed mop position.

The handle is shown broken away in FIGS. 1 and 6, and partially shown in FIGS. 2, 3, 4 and 5 for convenience of illustration.
